Specification for Design.

Patented Jan. 4, 1916.

Application filed May 4, 1915. Serial No. 25,853. Term of patent 14 years.

To all whom it may concern:

Be it known that I, SHEPARD J. GOLDBERG, a citizen of the United States, residing at the city of New York, borough of Brooklyn, Kings county, and State of New York, have invented a new, original, and ornamental Design for a Bottle, of which the following is a specification, reference being had to the accompanying drawings, forming part thereof, and in which—

Figure 1 is a side view showing a bottle made according to, and incorporating my

said design; Fig. 2 is a top view, partly in section on the line 2—2 of Fig. 1, and Fig. 3 is a sectional view taken on the line 3—3 of Fig. 1.

I claim:—

The ornamental design for a bottle as shown.

SHEPARD J. GOLDBERG.
